INDUCTIVE TUNING SYSTEM

Wladimir J. Polydoroff, Chicago, Ill., assignor to
 Johnson Laboratories, Inc., Chicago, Ill., a corporation of Illinois

Original application April 22, 1933, Serial No.
 667,368. Divided and this application November
 28, 1934, Serial No. 755,096. In Germany
 December 16, 1933

6 Claims. (Cl. 250—40)

The invention relates to radio receiving apparatus in which compressed magnetic cores are utilized as the tuning means. In such apparatus, the magnetic cores are arranged to be relatively movable with respect to the inductance coils, and the variation of the inductance, which produces the variable tuning, is brought about by varying the effective permeability of the space surrounding the coils. It is therefore conveniently called "permeability tuning" to distinguish it from other methods of inductance variation, and from methods in which the capacity is varied.

The several comminuted compressed magnetic cores and inductance devices which are described in this specification are disclosed in my co-pending applications No. 523,112, for Magnetic core material, Patent No. 1,982,689, issued December 4, 1934; No. 535,606, for improvements in high-frequency inductance devices, and No. 609,159, for Improvements in variable inductance devices, Patent No. 2,005,203, issued June 18, 1935, and hence no claims covering such improvements per se are herein included.

In permeability-tuned systems containing several tuned circuits, and intended to be tuned by a single control handle, there arises the problem of so designing and constructing the tuning unit that all of the circuits will be tuned very closely to the same frequency for each setting of the single control. This is accomplished partly by designing and constructing the magnetic cores and the inductance coils so that they will be closely alike, partly by providing a mechanism which will insure that the cores (or the coils) will move in unison, and partly by providing adjusting means, so that any unavoidable discrepancies in the cores, the coils, or the operating mechanism, can be compensated for.

Adjusting means to correct for errors of alignment are shown in Figs. 1, 2, 3 and 6 and are described in detail and claimed in my co-pending application, Serial Number 667,368, filed April 22, 1933, of which the present application is a division.

A principal object of my present invention is the provision of switching means by which a receiving apparatus of the permeability-tuned type may be made to satisfactorily cover a much wider band of frequencies than would be conveniently possible by the variation of inductance alone. Other objects of the invention, and advantages secured by its employment, will also appear from what follows.

My present invention, therefore, contemplates

that reasonable care will be taken to make the inductances alike, and that the cores, manufactured in accordance with my co-pending application, will also be closely alike. I then provide, in the present invention, in addition to mechanism for producing the necessary motion in unison of the several cores (or coils), the switching means hereinafter more fully described.

The invention will be better understood if reference is made to the accompanying drawings, which are illustrative of preferred embodiments, and wherein—

Figure 1 is a plan view of an assembly of several high-frequency devices, in one unit, parts being broken away to reveal subjacent elements; 15

Figure 2 is a sectional view of said unit taken on the line 2—2 of Figure 1;

Figure 3 shows certain modifications of the tuning elements;

Figure 4 shows diagrammatically a receiving 20 circuit employing one of the new high-frequency units;

Figure 5 shows switching means for altering the electrical constants of the circuits; and

Figures 6 and 7 show modifications of the high- 25 frequency device.

The unit disclosed in Figures 1 and 2 has four shielded variable inductance devices arranged to operate simultaneously. This unit has a foundation plate 1 that is provided with flanges 2 30 to which rectangular shields 3 are removably secured by friction or by other means, and with ribs 2a which serve as mountings for removable semi-adjustable condensers 4. A perforated lug 1a rising from an edge of said plate, enables the 35 unit to be connected with a suitable support.

Said foundation plate 1 also is provided with hexagonal tubular thimbles 5 through each of which extends a longitudinally movable screw-threaded rod 6 which terminates outside of the foundation plate 1, where it is provided with an adjusting nut 7. Fixed to the inner end of each of said rods 6, is a coil form 8 having a hexagonal cavity 9 into which the hexagonal thimble 5 extends, the depth of this cavity being such as to permit said coil form to move longitudinally relatively to said thimble, but without disengagement therewith, said coil form, while thus moving, being prevented from rotating by its hexagonal engagement with said thimble. A helical spring 40 45 50 55 10 is disposed between said foundation plate 1 and each of said coil forms 8, in order to maintain said coil forms in their adjusted positions. Each of said coil forms 8 has a flared wall 11 and is open at the end 12, and carries an induct- 55

ance coil 13. The mechanism just described constitutes means for adjusting the positions of each of the coils 13 with reference to the cores 34, 39.

Said foundation plate 1, furthermore, is provided with tubular sockets 14 for guide rods 15 which are parts of the mechanism for relative motion in unison between the several coils and cores of the unit.

The flanges 2, the hexagonal tubular thimble 5, 10 and the tubular sockets 14, may be made integral with the plate 1, as by die casting, or may be separately produced and secured to said plate in any suitable manner.

Associated with and movable toward and from 15 said foundation plate 1, is a core carrier 16, to which an actuating rod 19 is attached, said rod being in frictional engagement with a shaft 24. Said carrier 16 has holes 20 in which the ends of 20 guide tubes 21 are fixedly secured. The guide rods 15, carried by the foundation plate 1, telescope with and accurately fit these guide tubes.

Carried by the aforesaid core carrier 16, are 25 magnetic cores 56. These magnetic cores cooperate with the inductance coils 13 in such a way as to vary the effective permeability of the space surrounding the coils. Each magnetic core has a shell 34 having, in the head 36, an internally-threaded bushing 37 through which a screw-threaded rod 38 extends, and in which said rod is 30 longitudinally adjustable.

Said core also includes a plug 39 into which is moulded the inner end of said rod 38. The shell 34 may be spaced from the core carrier 16, by an 35 insulating washer 40 to exclude undesired influences of the metal core carrier on the core, and to leave room for a lock nut 41 which engages the screw threads of said rod 38, and, by contact with the head 36 of the shell 34, locks said plug 39 in any one of its chosen positions.

The aforesaid construction allows both the plug 39 and the shell 34 to be made separately and assembled by simply screwing the rod 38 into the bushing 37 of the outer shell, and then tightening the nut 41 until it locks said parts together.

Each of the condensers is desirably disposed 45 within one of the shields 3, whereby individual circuits are shielded from external influences and from each other. Hence, the problem of shielding inter-connecting wires between different parts 50 of the same circuit is eliminated. The shields have holes 3a affording access to the adjusting screws 54.

In some cases it is desirable to have two values 55 of capacity in each circuit, as shown in Figure 3.

Figure 3 shows two condensers 4a, 4b, having different capacity values and mounted on ribs 2a.

The plug of the magnetic core and the coil 13a may, as shown in Figure 3, be cylindrical, and said 60 coil may be bank wound, with several layers of wire.

In my co-pending applications No. 535,606 and 65 No. 609,159, an improved variable inductance device, consisting, for example, of a core 34, 39, a coil 13 and shield 3, is adequately described, and it is there pointed out that such a device is capable of maintaining a substantially constant ratio between the inductance and the radio-frequency resistance. This property is secured by the appropriate design and construction of the core and 70 by so designing the coil that the inductance-to-resistance ratio of the coil itself will have any desired value.

The selectance (expressed as the width of the 75 resonance curve at half amplitude) of the coil 13

of Figure 2 at 1500 k. c., with the core removed, will be approximately 22 k. c. With the improved core inserted into the coil, the selectance will be 18 k. c. at a frequency of 550 k. c. By giving the core a factor of merit better than the inductance-to-resistance ratio of the coil, although the uniformity of performance is somewhat impaired, the average properties of the circuit throughout the tuning range are improved. This is especially valuable in the case of a large inductance coil, 10 bank wound.

The coil 74 of Figure 6 is intended for very high amplification or for operation in more than one tuning range, and has approximately twice as many turns as the coil 13 of Figure 2. The winding 15 is of so-called Litz wire and is bank-wound. The inductance-to-resistance ratio of this coil is of the order of 7.5×10^{-6} at 1500 k. c.

Using a core whose factor of merit is 20×10^{-6} , the inductance-to-resistance ratio of the combination at 550 k. c. is of the order of 10×10^{-6} , and the selectance of the system varies from 42 to 30 k. c. Using the same coil 74 to tune from 500 k. c. to 180 k. c., it has an inductance-to-resistance ratio of the order of 40×10^{-6} at 500 k. c., and of 25 the order of 45×10^{-6} at 180 k. c. The selectance of the circuit in this new band of frequencies is of the order of 8 k. c. Thus, a considerable change in the selective properties of the circuits occurs if the same variable inductance device is used for 30 two different bands of frequencies.

Under normal conditions of design and operation, for every operating frequency within the range of adjustability, there is a corresponding 35 position of the cores relative to the coils in which they produce an effective permeability in each of the coils such as to tune the several circuits to that frequency.

It is possible, however, to decrease the ratio at any desired frequency by the expedient of inserting 40 the cores further into the coils to produce a higher effective permeability and therefore a higher effective inductance, but, at the same time, re-tuning to the desired frequency by readjusting the values of the capacities. By this expedient, 45 the inductance-to-resistance ratio can be made considerably less than it would otherwise be, with a resultant decrease in the selectivity, which corresponds to a broadening of the selectivity curve. As is well known, the fidelity of radio circuits is 50 determined by the sharpness of the resonance curves. The sharper the curves are, the more they discriminate against the higher modulation frequencies of the signal.

The expedient just described, therefore, provides 55 a simple method of broadening the selectivity and improving the fidelity of such circuits at will. For example, when it is desired to obtain maximum discrimination between signals, the circuits are tuned in the usual manner by 60 moving the cores in accordance with the initial adjustments. When it is desired to improve the fidelity for a particular signal, a smaller capacity may be employed in each of the circuits and the cores moved further into the coils to again tune 65 the several circuits to the desired signal.

Figures 4 and 5 show an arrangement for a radio receiving apparatus, in which a capacity switching arrangement is employed. This may be done to control the fidelity in the receiver, as 70 just described, or it may be employed to produce an arrangement which can be tuned over two or more different ranges of frequency. The variable inductances include coils 13 and cores 56 which, with the capacities 57, form resonant circuits ar- 75

ranged in cascade with the thermionic amplifiers 58. The signal received on the antenna 59 is fed to the first tuned circuit through a capacity 62. Between the two thermionic amplifiers two resonant circuits may be capacitively coupled through either of the capacities 63, 64, or both. The plate circuit of the second thermionic amplifier is connected through a capacity 65 and a grid leak 66 with the detector amplifier 67, which is of the diode-triode type. This detector amplifier supplies audible signal for the output amplifier 68, and also supplies automatic volume control bias regulation to the high-frequency thermionic amplifiers 58.

15 When the switches 69 are in the position shown in Figure 4, all the circuits are responsive to the high-frequency band of the receiver, say 550 to 1500 k. c., with the antenna coupled through the condenser 62, and the bi-selector coupled through the capacity 64. When all the switches 69 are turned to the left, the capacities 57b, 57c, 57d and 57e are added to the circuits and the antenna coupling capacity is increased by the addition of condenser 57a, and the bi-selector coupling is also increased by the addition of condenser 63, thus changing the circuit constants so that the receiver will tune over a lower frequency band.

20 The switching may be conveniently accomplished by a two-way switch, such for example as that shown in Figure 5, which may be mounted on the back plate 1 of Figures 1 and 2. The switch consists of a drum 70 made of insulating material and rotating through an angle of 90 degrees on a grounded metal shaft 71. On the 25 drum 70 there are conductive inlays 72, some of which are connected to the grounded shaft 71. The position of the switch shown in Figure 5 corresponds to the condition in Figure 4 when all the switches 69 are thrown to the left.

30 As has been pointed out, the same variable inductance device, when designed for two operating frequency ranges, will exhibit different selectivity and different gain in the two frequency ranges. To compensate for the difference in the two characteristics, the switch can be arranged to provide weaker coupling of the antenna to the first tuned circuit, and weaker coupling of the two circuits in the bi-selector, for the high-frequency range. The couplings are then automatically increased 35 when the lower frequency range is in use.

35 Another method of securing operation in two frequency ranges, is indicated in Figure 6, where two separate coils 73 and 74 are arranged to be acted upon by the core or cores 56. The coil 73 is similar to the coil 13 of Figure 2 and is designed to operate over a range of frequencies from 550 to 1500 k. c., with a suitable condenser. The coil 74 is bank-wound to cover a new range of frequencies, such as from 180 to 500 k. c., either with 40 the same condenser or with a suitable additional capacity.

45 The core 56, or a group of similar cores, may be arranged to be moved laterally so as to engage with either set of coils. In an alternative arrangement, the coils may be arranged to move laterally, leaving the cores movable only in the original translatory manner.

50 It is also possible to mount the several coils for a particular frequency range on a plate 75, as shown in Figure 7, so arranged that the entire group of coils may be removed and replaced by a second group of coils designed to cover a different frequency band.

Having thus described my invention, what I 55 claim is:

1. A multi-range system for a radio receiver including a plurality of tuned circuits each having inductance and capacitance, magnetic cores associated with said inductances, tuning means for producing simultaneous movement of said cores relatively to said inductances, coupling between at least two of said circuits, and switching means for altering said capacitances and said coupling, the values of said capacitances and of said coupling being so chosen that said system 10 may be tuned over a plurality of frequency ranges and will have substantially the same performance characteristic in each of said ranges.

2. A multi-range system for a radio receiver including an antenna circuit and a plurality of 15 tuned circuits each having inductance and capacitance, magnetic cores associated with said inductances, tuning means for producing simultaneous movement of said cores relatively to said inductances, coupling between at least two of 20 said circuits, and switching means for altering said capacitances and said coupling, the values of said capacitances and of said coupling being so chosen that said system may be tuned over a 25 plurality of frequency ranges and will have substantially the same performance characteristic in each of said ranges.

3. A tuning unit for a radio receiver including a pair of tuned radio-frequency circuits each having an inductance coil and a capacitance, 30 unitary tuning means for simultaneously varying the effective inductance values of said coils, a coupling capacitance connected between said circuits, plural additional capacitances and a multiple switch adapted to connect one of said additional capacitances into each of said circuits and to connect another of said additional capacitances between said circuits.

4. A tuning unit for tuning a radio receiver over upper and lower frequency ranges, including 40 a pair of tuned radio-frequency circuits each having an inductance coil and a capacitance, said inductance coils being bank wound to a value suitable for said upper and lower ranges, unitary means for simultaneously varying the 45 inductance values of said coils, a coupling capacitance connected between said circuits, plural additional capacitances and a multiple switch adapted to connect one of said additional capacitances into each of said circuits and to connect 50 another of said additional capacitances between said circuits, the value of said coupling capacitance being so chosen that said receiver will have substantially the same performance characteristic in said upper and lower ranges.

5. A system for operating a radio receiver over upper and lower frequency ranges having in combination a pair of coupled resonant circuits each including an inductance and a capacitance, said inductances each being bank wound, means for increasing said inductance values to select desired signals in either of said ranges, a coupling capacitance connected between said circuits, plural additional capacitances and a multiple switch adapted to connect one of said additional 60 capacitances into each of said circuits and to connect another of said additional capacitances between said circuits, the value of said coupling capacitance being so chosen that said receiver will have substantially the same response to signals in either of said ranges.

6. A system for operating a radio receiver over upper and lower frequency ranges having in combination a pair of coupled resonant circuits each including an inductance and a capacitance, 70

5 said inductances each being bank wound to a value suitable for said upper and lower ranges, means for increasing said inductance values to select desired signals in either of said ranges, a coupling capacitance connected between said circuits, plural additional capacitances and a

multiple switch adapted to connect one of said additional capacitances into each of said circuits and to connect another of said capacitances between said circuits.

WLADIMIR J. POLYDOROFF. 5
